UNITED STATES PATENT OFFICE.

JOHN D. TARASOFF, OF CRESCENT VALLEY, BRITISH COLUMBIA, CANADA.

SWITCH-THROWING DEVICE.

1,320,184.

Specification of Letters Patent.

Patented Oct. 28, 1919.

Application filed May 14, 1919. Serial No. 297,114.

To all whom it may concern:

Be it known that I, JOHN D. TARASOFF, a citizen of Russia, residing at Crescent Valley, Province of British Columbia, and Dominion of Canada, have invented certain new and useful Improvements in Switch-Throwing Devices, of which the following is a specification.

This invention relates to improvements in means for actuating switch points as used in connection with the running rails of steam and street railroads.

The principal object of the invention is to provide a device arranged alongside of the track which may be operated by a passing car or locomotive by pressing a lever in advance of the switch so that the same will be moved prior to the entry of the car thereupon.

20 A further object is to provide means whereby the switch points are held firmly in either of their adjusted positions.

Another object is to provide means which are positive in their operation and comprised of few and simple parts.

These and other like objects are attained by the novel construction and combination of parts hereinafter described, and shown in the accompanying drawings, forming a material part of this disclosure, and in which—

Figure 1 is a fragmentary plan view, showing a section of a track including a curve and indicating the application of the invention.

Fig. 2 is a fragmentary side elevational view, partially diagrammatic and indicating the application of the operating means to a car.

40 Fig. 3 is an enlarged fragmentary plan view similar to Fig. 1.

Fig. 4 is a transverse sectional view, taken on line 4—4 of Fig. 3.

Fig. 5 is a similar transverse sectional view, taken on line 5—5 of Fig. 3.

Fig. 6 is another transverse sectional view, taken on line 6—6 of Fig. 3, and

Fig. 7 is another plan view, similar to Fig. 1 but showing a modification.

50 In the drawings, the numeral 10 indicates a through rail 11 the mating rail, the latter being bent outwardly at 12, the straight rail 13 having pivoted to its end a tongue 14, while with the concentric rail 15 is similarly connected the switch tongue 16, all of the several rails resting upon ties or sleep-

ers 17, constituting a conventional type of railroad construction.

In Fig. 2 a car is indicated by broken lines 20, upon which is mounted a rigid bracket 21, having an operating lever 22 fulcrumed on the pin 23, and a sliding detent 24 engaging in openings 25 formed in the arcuate portion of the bracket 21.

The lower end of the lever is engaged 65 with the rod 27, pivoted to one of the arms 28 of a bell-crank lever, fulcrumed on a fixed bracket 29, the other arm 30 of the lever connecting with the link 32, engaged with a plunger 33, slidably mounted in a 70 bracket 34, attached transversely to the lower side of the car floor and adapted to be extended out by actuating the lever 22.

A plate lever 36 is pivotally secured to the rail 10 by bolt 37, and has fixed in it a post 75 38 with which the plunger 33 is adapted to make contact when in an extended position so as to cause the plate to pivot upon the bolt 37, moving it forward and actuating a link bar 40, pivoted to the plate 36 by a 80 pin 41.

The opposite end of the link bar 40 is engaged by a pivot 42 with a right angled triangular plate 45, pivoted on the bolt 46, the longer side of the triangular plate containing 85 a longitudinal slot 48 receptive of the down-turned end of a spring arm 49, the inner end of which enters a fixed casing 50, and is formed into coiled spring 51.

Engaged to the triangular plate 45, in the 90 outer corner substantially in register with the slot 48 is another pin 52 operating within a slot 54, formed in a head 55 of a bar 56 to which is attached the end of a switch-bar 56 adjacent to the head, the other extremity 95 of the bar being connected with a bracket 58, engaged with the switch point 14. Thus the bar 56 acts as a distance rod between the switch point and through which they are moved by the mechanism described.

100 From the foregoing it will be seen that when the plunger 33 is moved outwardly, it will engage with the upstanding post 38 and through its connections, cause the triangular plate 45 to rotate so that the end 105 49 of the spring element will move within the slot 48 into the position shown in broken lines in Fig. 3, thereby locking the switch points in either of their adjusted positions.

The modification illustrated in Fig. 7 110 shows a pair of fixed points 14 and 16 respectively, engaged by a pair of connecting

elements 56, operable independently by separate triangular plates 45, having spring actuating connections as before described, whereby they are held in adjusted position, 5 the adjustment being effected by the rods 40, which extend in opposite direction along the track rails 11 and 12 and are provided with operative devices 38, actuated in the main manner before described, the main difference being in the fact that the switch 10 may be thrown by a train approaching in either direction, and that the train operated devices may be used to move the switch point after the train has passed, leaving the 15 switch in condition for the next succeeding train.

I claim:

1. In a switch device, the combination with a pair of running rails and a pair of 20 switch points coöperative therewith, of a plate pivoted remotely from said switch point, an arm formed with said plate adapted to be operated by the car passing over said rails, a triangular plate pivoted to one 25 of said rails adjacent to said switch point, connections between said plates, a connecting bar extending between said switch points, and means formed with said triangular plate whereby said connecting bar is operated upon movement being communicated to the first named plate.

2. In a switch throwing device, the combination with a pair of running rails and a

pair of switch points operatively combined therewith, of a plate pivoted to one of said 35 running rails, an arm formed on said plate, means for actuating said arm, a triangular plate pivoted to the same rail adjacent to said switch points, connections between said plates whereby when said arm is moved said 40 triangular plate is caused to turn upon its pivot, an elongated slot formed in said triangular plate adjacent to the longer side thereof, a rigid casing secured alongside of said rail, a spring in said casing, an arm 45 extending from said spring into said slot whereby said plate is held in either adjusted position, and means engaged with triangular plate adapted to operate both of said switch points.

3. In a switch operating device, the combination with a pair of running rails, and a pair of switch points operatively combined therewith, of a triangular plate below one 55 of said running rails, an elongated slot formed in said triangular plate adjacent to the longer edge thereof, a bar connecting between said switch points, a casing fixed adjacent to said running rail, and a spring element in said casing having an arm extending outward into slot in said triangular plate whereby it may be held in either of 60 adjusted positions.

In testimony whereof I have affixed my signature.

JOHN D. TARASOFF.
